UNITED STATES PATENT OFFICE.

HARRY G. SUTTON, OF SYRACUSE, NEW YORK, ASSIGNOR TO THE ZEIDLER CORPORATION, OF NEW YORK, N. Y., A CORPORATION OF NEW YORK.

GARMENT PRESS.

Application filed May 6, 1927, Serial No. 189,383. Renewed August 9, 1928.

This invention pertains to improvements in garment presses.

The invention has for its main object the production of a simple and effective structure wherein the head, when the press is open, stands clear and well to the rear of the buck to afford the operator ready access to the garment or goods laid upon the buck in order to secure a proper lay thereof.

10 A further object of the invention is to provide a structure wherein the head, as it is moved forwardly over the buck, stands in spaced relation thereto so as not to drag across the goods imposed upon the buck and 15 when the head is brought in vertical alignment with the buck to provide means whereby the head may be moved downwardly at right angles to the face of the buck to effect pressure upon the goods and this without 20 any relative sidewise or swinging motion of the head with reference to the buck.

The press is shown in the annexed drawings wherein,

Figure 1 is a front elevation thereof partly broken away with the press shown in its closed position;

Figure 2 a vertical sectional view showing the press in the same relation; and

Figure 3 a similar view with the head 30 as thrown fully back and clear of the buck.

The frame of the machine may be of any approved type but in the instant case it is composed of a base member 1 to which are secured two vertically disposed members 2 and 3, preferably formed from sheet steel struck to the desired contour, each of said members being provided with a forward portion as 2^a and 3^a. Said members, in other words, are L-shaped in cross section and at 40 their upper ends are secured to a bed plate 4. Extending upwardly from the bed plate is the usual buck support 5 upon which is imposed the buck 6. The head is denoted by 7 and is secured to the forwardly extending 45 end of a frame of substantially inverted L-shaped outline. Said frame may be said to comprise a body or transverse web element 8 provided with rearwardly extending flanges 9 and 10 at each side of the web member.

50 At the lower end of each of the webs 9 and 10 they are enlarged and each web in such enlarged portion is provided with a slot having a slightly curved section 11, the forward end of which merges into an upstanding or 55 vertical short section 12. In other words,

the lower section 11 guides the head frame forwardly from the full open position to carry the head to the dotted line position in Figure 3 immediately above and in direct alignment with the buck while the short vertical section allows the head carrying frame and the head to be moved downwardly in a right line into contact with the goods imposed upon the buck.

Secured to the side wall 2 is a stub axle 13 upon which is mounted a roller 14 which enters the slot in the web 9. A small stub axle 15 is mounted in the other side frame 3 and a roller 16 extends into the slot formed in the web 10. These rollers therefore act as guides for the lower end of the head carrying frame.

Secured to the forward face of the web 8 of the head frame are brackets 17 and 18 which carry pins 19, to which pins are secured blocks 20 threaded to receive the lower ends of springs 21 and 22. The springs at their upper ends are attached in any suitable manner to a fixed portion of the machine frame as, for instance, the bed plate 4 and are under tension at all times so that they have a tendency to raise the lower end of the head frame upwardly and throw it to the full open position shown in Figure 3.

Two pair of links are associated with the head carrying frame to cause it to move in the desired path and to this end there is pivotally secured to the side plate or frame member 2, as at 23, a link 24 the upper forward end of said link being pivotally connected as at 25 to a second link 26 which in turn is pivotally connected to a bracket 27 secured to the web 8. A second pair of links is associated with the side frame 3 and the head frame. The lowermost link 28 is pivoted, as at 29, at its lower end to the plate 3 and extends upwardly and rearwardly and is pivotally connected as at 30 to the second link 31, said link in turn being pivotally connected as at 32 to a bracket 33. These two pair of links, while shown as extending in opposite directions, might both extend in the same general direction though the arrangement illustrated is preferred inasmuch as they tend to counteract each other in so far as any twisting motion of the head frame is concerned.

It will be noted that the pivotal connection of the upper ends of the links 26 and 31 are in alignment and that the linkages, above

described, form in effect a floating pivotal support or fulcrum for said head carrying frame.

Extending downwardly from the under side of the bed plate 4 is a rigid bracket 5 34 which forms the support for a bell-crank lever fulcrumed upon the shaft 35. The lower end 36 of the bell-crank lever has pivotally attached thereto a link 37 which in turn, at its lower end, is pivotally attached to a bracket 38 secured to the lower forward face of the head carrying frame. The upper arm 39 of the bell-crank lever has pivotally attached to it a pair of draw links 40 and 41, said links at their lower ends being pivotally connected to a treadle lever 42 fulcrumed as at 43 to upstanding brackets 44 formed at the rear of the base frame 1. The forward end of the lever is fashioned into a treadle 45 and associated therewith is a latch 46 adapted, when the head is fully closed down upon the buck, to engage a fixed portion of the machine and hold the press in its closed position.

It is thought that from the foregoing the 25 operation of the press will be clearly understood but a short résumé will be given. Assuming that the parts are in the position shown in Figure 3, it is to be noted that the head stands to the rear of the buck so that 30 the operator may readily secure the proper lay of the goods upon the buck. He then depresses the treadle 45 or may draw the head forwardly by grasping a handle 47 secured to the forward end of the head 35 carrying frame. This will cause the head carrying frame to swing forwardly, the lower portion of the frame traveling over the rollers working in the substantially horizontal slightly curved portion of the slots, or in other words the portion 11, the linkages 24—26 and 28—31 co-operating therewith to bring the head forwardly and in 40 spaced relation to the buck.

When the lower portion of the head carrying frame reaches a position where the 45 rollers 14 and 16 stand in alignment with the lower portion of the vertically disposed section 12 of the slots, the head carrying frame will be thrust downwardly by further 50 downward movement of the link 37 and thus the head will be lowered in a right line directly upon the goods imposed upon the buck without any wiping or drawing action of the head thereover.

55 When fully depressed the lever 42 will become locked and the goods may be maintained under pressure as long as desired. The operator may, of course, pat the goods by holding the latch 46 out of operation 60 by merely placing his toe thereon.

What is claimed is:

1. In a garment press the combination of a frame; a buck supported thereby; a head carrying frame of substantially inverted L-shaped outline; a head secured to the for-

wardly extending portion thereof, said frame in its lower portion being provided with a pair of slots, each slot having at the forward end thereof a substantially vertical portion, and a longer, slightly curved, substantially horizontally disposed portion extending rearwardly therefrom; rollers secured to the frame, said rollers entering said slots; means acting at all times to raise the lower end of the head carrying frame; a shifting fulcrum for the head carrying frame; and means for forcing the lower end of said head frame downwardly.

2. In a garment press the combination of a frame; a buck thereon; a head carrying frame having a downwardly extending portion; a head carried by the upper portion of said frame; a pair of rollers supported upon opposite sides of the frame, said rollers extending into guide slots extending substantially horizontally at the lower portion of the head frame, said slots having a vertically disposed portion at the forward ends thereof; a shifting fulcrum for the head frame located at a point above the slots; means acting at all times upon the head frame to raise the same; and means for forcing the lower end of the head frame downwardly.

3. A garment press as set forth in claim 2 wherein the shifting fulcrum is produced by links connected respectively to the machine frame and the head carrying frame.

4. A garment press as set forth in claim 2 wherein the shifting fulcrum is produced by a pair of links to each side of the lower portion of the head frame, the links of each pair being pivoted to each other and the other ends pivoted, respectively to the machine frame and the head carrying frame.

5. In a garment press the combination of a frame having two spaced vertically disposed side walls; a buck supported on the frame; a head carrying frame having an upper forwardly extending portion, the lower end of said frame extending downwardly and inwardly of the side walls aforesaid, said lower end having oppositely disposed guide slots, each slot having a horizontal section merging at its forward end into a vertically disposed section; rollers carried by the machine frame entering said slots; spring means acting upon the lower end of the head frame to draw the same upwardly; a pair of pivotally connected links arranged to each side of the lower end of the head frame, the lower link of each pair being pivoted to the adjacent side wall, while the upper end of each pair is pivotally connected to the head frame; and means for exerting a downward thrust upon the lower end of the head frame.

In testimony whereof I have signed my name to this specification.

HARRY G. SUTTON.
